UNITED STATES PATENT OFFICE.

HARRY T. RASER, OF ASHTABULA, OHIO.

OIL-ENGINE.

1,163,604:

Specification of Letters Patent. Patented Dec. 7, 1915.

Application filed December 29, 1914. Serial No. 879,486.

To all whom it may concern:

Be it known that I, HARRY T. RASER, a citizen of the United States, residing at Ashtabula, in the county of Ashtabula and State of Ohio, have invented certain new and useful Improvements in Oil-Engines, of which the following is a specification.

This invention relates to an improvement in internal combustion engines.

10. One of the principal objects of the invention is to provide an improved internal combustion engine or attachment in which the firing mixture is ignited through the heat generated by the compression alone of the mixture.

15. Another object is to provide an internal combustion engine with an attachment in the shape of an auxiliary cylinder in which the firing mixture may be compressed or partially ignited, means being provided whereby progressive ignition will ensue in a larger or main cylinder for obtaining complete combustion and a maximum degree of expansion whereby to drive the main piston.

20. Still another object of the device is to provide an improved engine of the class described having main and auxiliary cylinders in tandem, the latter being of smaller bore than the former, and having an auxiliary 25 piston connected with and operable coincident with the main piston and adapted to operate in the auxiliary cylinder for compressing the firing mixture to the required degree therein, the arrangement being such 30 that when partial combustion takes place in the mixture the latter is allowed to escape into the main cylinder and commingle with the air therein to attain the complete combustion and expansion for driving the main 35 piston.

40. A further object of the invention is to provide an engine of the class described which will be extremely simple, durable, efficient in operation and inexpensive to 45 manufacture.

With these and other objects in view which will become apparent as the description proceeds, the invention resides in the construction, combination and arrangement 50 of parts, hereinafter more fully described and claimed, and illustrated in the accompanying drawing, in which like characters of reference indicate like parts throughout the several figures, of which—

55. Figure 1 represents a view in section taken centrally through the cylinders of an

engine constructed according to my invention. Fig. 2 represents an enlarged view in section taken through the auxiliary cylinder showing the air intake valve and fuel control valve in detail. Fig. 3 represents a view in section taken horizontally on the line 3—3 of Fig. 2.

In the drawing I have shown a two cycle engine constructed and operated on the principle involved in my invention, but it is understood that the principle is equally applicable to engines of the four cycle type.

In the drawing the crank case is indicated at 5, the main cylinder at 6, the auxiliary cylinder at 7, the main piston at 8, and the auxiliary piston at 9. The main and auxiliary cylinders are arranged in tandem, the latter as indicated having a bore much smaller in diameter than the bore of the main cylinder 6. Piston 9 is rigidly connected to the main piston through the medium of a stem 10.

Arranged in the head 11 of the cylinder 7 is the intake valve 12. It controls the inlet 80 of air and oil to the auxiliary cylinder, being adapted to open upon downward stroke of piston 9 for filling the auxiliary cylinder with the combustible mixture of air and oil, and adapted when the piston 9 moves 85 upwardly, to close, whereby to cut off the supply of air and oil.

Any suitable fuel may be used, the engine being adapted to handle oils in their various refined or unrefined state for the production 90 of power.

A fuel tank is indicated at 13 and communicates by means of a pipe 14 with a passage 15 in the cylinder head 11. Said passage at its inner end is adapted to be controlled by 95 valve 12, and the flow of oil through the passage is controlled by the fuel regulating valve 16.

An air passage 17 leads from the crank case to the cylinder 6, and communicates 100 with the latter at a point substantially in alinement or slightly above the upper surface of piston 8 when the latter is in its lowermost position. An air intake point 18 is provided in the cylinder and controlled by 105 piston 8, said port being opened for allowing admission of air to the crank case, when the piston is in its uppermost position, and being closed by the piston in its downward movement.

110 The exhaust manifold is indicated at 19 and communicates with cylinder 6 opposite

the upper end of passage 17, through the exhaust port 20.

The walls of auxiliary cylinder 7 near the upper end of said cylinder, are provided with a plurality of diametrically opposed grooves 21 having concaved floors 22. The grooves run longitudinally of cylinder 7 and are somewhat longer than the piston 9 is wide.

10 The engine may be started in the usual way, and by mechanical means or manually.

The operation of the engine is as follows: Upon the down stroke of piston 9 the valve 12 is opened admitting a mixture of oil and 15 air into the auxiliary cylinders. As the piston 9 moves upwardly it compresses the combustible mixture to such a degree that just as the piston reaches a point in cylinder 7 coincident with the lower ends of the 20 recesses or ports 21, the compression attains such a degree that the heat of the compressed gases vaporizes and ignites them, and as the piston 9 moves upwardly past the ports 21, in finishing its upward movement, the burning 25 gases pass around the piston through the ports 21 as they are uncovered, and meet the air in the cylinders 7 below the piston and in the upper portion of cylinder 6 above piston 8, (which it will be understood moves coincidently with piston 9), whereby complete 30 combustion of the gases takes place resulting in an expansion, which drives the piston 8 downwardly. As the latter moves downwardly it closes inlet port 18 and compresses 35 the air in the crank case 5 and upon the uncovering of the opening at the upper end of passage 17, the compressed air in the crank case rushes upwardly through passage 17 into the cylinder 6, as the burnt gases contained 40 in said cylinder exhaust through port 20 into the exhaust manifold. Upon the return upward movement of piston 8 port 20 and the opening at the upper end of passage 17 are simultaneously closed, and the inlet 45 port 18 is opening as the piston reaches the upper terminal of its stroke, so that air may again be admitted to the crank case, and the operation continues as described. The area of piston 8, is of course greater than the 50 area of piston 9 so that upon combustion taking place in the cylinder, piston 8 will be driven down as stated. The length of cylinder 6 is such, that when the piston 8 is at the upper end of its stroke, there will be a space 55 between said piston and the auxiliary cylinder 7, which space is filled with compressed air above the piston.

The cylinder 7, is formed with an annular outwardly extending flange at its lower end, which flange forms the head of cylinder 6. The flange is connected by machine bolts or other suitable fastenings 23 to the upper end of cylinder 6.

Although I have described the preferred 65 embodiment of my invention, I may desire

to make such changes in the construction, combination and arrangement of parts thereof as do not depart from the spirit of the invention and the scope of the appended claims.

70 I claim:

1. An internal combustion engine comprising a main and an auxiliary cylinder arranged in tandem, said auxiliary cylinder being of a smaller diameter than the main cylinder, a piston movable within the main cylinder, an auxiliary piston movable within the auxiliary cylinder, a stem fixedly connecting the main and auxiliary pistons, an intake valve arranged in the head of the auxiliary cylinder and adapted to control the intake of air and fuel, said valve adapted to be opened upon downward movement of the auxiliary piston for drawing the combustible mixture into the auxiliary cylinder, said auxiliary cylinder provided with a plurality of recesses in its inner walls and extending longitudinally thereof, said recesses being disposed adjacent the upper end of said auxiliary cylinder, said recesses being of a length somewhat greater than the width of the auxiliary piston, said auxiliary piston adapted as it moves upwardly within the auxiliary cylinder, to compress the combustible mixture contained in the latter to the point of ignition whereby the burning mixture will pass around the auxiliary piston into the cylinder below the piston as said piston uncovers said recess, substantially as described.

75 2. An internal combustion engine comprising a main cylinder and an auxiliary cylinder arranged in tandem said auxiliary cylinder being of a diameter less than the diameter of the main cylinder, a main and an auxiliary piston fixedly connected together and adapted to reciprocate respectively in the main and auxiliary cylinders, said auxiliary piston adapted to compress a combustible mixture within the auxiliary cylinder to the point of ignition, a valve for controlling the admission of the combustible mixture to the cylinder, said auxiliary cylinder being provided with recesses adapted to be uncovered by the auxiliary piston as the mixture ignites, whereby to allow the burning mixture to pass around the piston into the cylinder below said auxiliary piston, substantially as described.

80 3. An internal combustion engine including a crank case, a main cylinder connected therewith, a passageway communicating with the crank case and main cylinder, an inlet port adapted to admit air into the crank case, an exhaust port communicating with the main cylinder, a main piston adapted to reciprocate within the main cylinder, and adapted to control the inlet and exhaust ports and the said passageway, an auxiliary cylinder arranged in tandem rela-

- tion with the main cylinder, an auxiliary piston adapted to reciprocate within the auxiliary cylinder and fixedly connected with the main piston, said auxiliary piston 5 adapted to compress a combustible mixture within the auxiliary cylinder above said auxiliary piston, means for controlling the admission of combustible mixture to the auxiliary cylinder, and means associated 10 with the auxiliary cylinder and adapted as the point of ignition is reached by the compressed mixture, to allow passage of the burning mixture into the cylinder below the auxiliary piston, substantially as described.
- 15 4. An internal combustion engine including a main and an auxiliary cylinder arranged in tandem, main and auxiliary pistons adapted to reciprocate respectively in the main and auxiliary cylinders and being 20 fixedly connected together, said auxiliary piston adapted to compress a combustible mixture within the auxiliary cylinder to the point of ignition, said auxiliary cylinder provided with ports adapted to be uncovered 25 by the auxiliary piston as the compressed mixture reaches the point of ignition for allowing
- lowing passage of said mixture into the cylinder below the auxiliary piston, and means for controlling the admission of combustible mixture to the auxiliary cylinder. 30
5. In an internal combustion engine, the combination with a main cylinder and piston of an auxiliary cylinder and piston, said auxiliary cylinder being in open communication with the main cylinder, said main and auxiliary pistons being fixedly connected together, a fuel supply, means communicating with the auxiliary cylinder and fuel supply above the auxiliary piston, means for controlling the admission of fuel and air to the auxiliary cylinder, said auxiliary piston adapted to compress the combustible mixture to the point of ignition within the outer end of the auxiliary cylinder, and means for allowing passage of the burning mixture 45 into the auxiliary cylinder below the auxiliary piston, as the point of ignition is reached. 40
